Attorneys:

UNITED STATES PATENT OFFICE.

FRANK W. MERRICK, OF BOSTON, MASSACHUSETTS.

DESIGN FOR A SEAM-WELTING STRIP.

SPECIFICATION forming part of Design No. 29,914, dated December 27, 1898.

Application filed November 25, 1898. Serial No. 697,456. Term of patent 14 years.

To all whom it may concern:

Be it known that I, FRANK W. MERRICK, a citizen of the United States, residing at Boston, in the county of Suffolk and State of Massachusetts, have invented and produced 5 a new and original Design for Seam-Welting Strips, of which the following is a specification, reference being had therein to the accompanying drawing.

o The drawing is a perspective, on an enlarged scale, of a short portion of a seam-welting strip embodying my design.

The characteristic features of my design are the rounded side 1, resembling, in effect

or appearance, a cord or bead, and the scores 15 or grooves 2, extending lengthwise of the strip and confirming or enhancing the said effect or appearance, the strip in its entirety being thin and narrow.

I claim as my invention—

The design for a seam-welting strip, substantially as shown.

In testimony whereof I affix my signature in presence of two witnesses.

FRANK W. MERRICK.
